BOTTLE CLEANER OR THE LIKE

Earl S. Tupper, Upton, Mass.

Application January 12, 1955, Serial No. 33,941

Term of patent 14 years

(Cl. D44—29)

Figure 1 is a perspective view of a bottle cleaner or the like embodying my new design;

I claim:

The ornamental design for a bottle cleaner or the like, as shown.
